UNITED STATES PATENT OFFICE

133,544

DESIGN FOR A FONT OF HEBRAIC TYPE

Isaac Schild, Brooklyn, N. Y.

Application November 26, 1941, Serial No. 104,341

Term of patent 14 years

To all whom it may concern:

Be it known that I, Isaac Schild, a citizen of the United States, residing at Brooklyn, in the county of Kings and State of New York, have invented a new, original, and ornamental Design for Font of Hebraic Type, of which the following is a specification, reference being had to the accompanying drawing, forming part thereof.

The figure is a face view of a front of Hebraic type showing my new design.

I claim:

The ornamental design for a font of Hebraic type, substantially as shown.

ISAAC SCHILD.
